UNITED STATES PATENT OFFICE.

CLARENCE WILBUR WHITE, OF CHICAGO, ILLINOIS.

BOAT OR SHIP CONSTRUCTION.

1,241,799.

Specification of Letters Patent.

Patented Oct. 2, 1917.

Application filed March 1, 1916. Serial No. 81,400.

To all whom it may concern:

Be it known that I, CLARENCE WILBUR WHITE, a citizen of the United States, residing at Chicago, in the county of Cook and State of Illinois, have invented a new and useful Improvement in Boat or Ship Construction, of which the following is a specification.

My present invention relates to boat or ship construction applicable to both over sea and under sea types.

The principal objects of my invention are to provide a boat or ship so constructed that the hull may be quickly raised or lowered with respect to the water line or water level; to provide a boat or ship embodying a hull which is comparatively inexpensive to construct and maintain in good repair; to so dispose the hull that the lower portion is normally open to the sea bottom and its upper portion normally closed to the atmosphere so that the boat is sustained extending above the water surface by air entrapped or forced into the hull; and, to provide a boat or ship embodying means whereby an opening accidentally or maliciously formed in the hull will be effectively closed to prevent sinking or submerging of the vessel.

Another object of the invention is to provide a boat or ship embodying a keel which will not become damaged should it run afoul, and means whereby the hull with the keel may be raised off ground in order to free the boat or ship of a reef, shoal or other obstruction.

Other objects of the invention will appear in the following detailed description, taken in connection with the accompanying drawings forming a part of this specification, and in which drawings:

Figure 1 is a side elevation of a ship constructed according to my invention.

Fig. 2 is an enlarged partial transverse sectional view through the same.

Fig. 3 is a sectional view on the line 3—3 of Fig. 2, looking in the direction of the arrow.

Fig. 4 is a longitudinal sectional view through a portion of the wall of the hull, showing plates in operative relation thereto.

In the drawings, where similar characters refer to similar parts throughout the several views, A designates the hull having an

open bottom B an upper portion C closed to the atmosphere; D a keel; E a waist; F means for introducing fluid under pressure to within the hull A; G means for releasing fluid pressure from within the hull; H supplemental means or a storage tank for supplying fluid under pressure to within the hull; and J, means for automatically closing any opening in the hull below the waist E which may be accidentally or maliciously formed therein.

Referring first to the hull A, for the sake of simplicity, all structural members such as braces, stringers and the like have been omitted from the drawings, the hull being of the usual shape but when launched the open portion B of its main cavity is lowermost, and submerged in the water, so that air or fluid under pressure is confined within the hull, and more specifically above the water line 5, within the hull, which fills the cavity 6.

Any suitable means, such as the keel D, extending longitudinally of the hull and supported as by braces 7, may be provided to stabilize the hull and prevent it from turning turtle. The keel may be of any suitable material, preferably metal, so that it is not likely to become damaged if engaging a reef, the keel being rounded, as indicated at 8, at the bow and also rounded as indicated by character 9 at the stern.

In order to provide means for supporting decks and a protection for mechanism to be used hereinafter described, a suitable waist, preferably of metal, is secured to the closed upper portion of the hull and may be provided with port holes 10, of any suitable type to exclude water from entering within the waist. Since the hull may be raised and lowered with respect to the water line by introducing fluid pressure within the cavity 6 or exhausting it therefrom, it is preferred to extend the waist E into close proximity to the water line so that if desired the vessel may be lowered sufficiently to project only slightly above the water line, or become entirely submerged, as in a submarine type of vessel.

Any suitable means may be provided for introducing fluid under pressure to within the hull A, and as shown in the drawings, means F comprises a pump 11, supply pipe 12 in communication with the cavity 6,

check valve 13 in said pipe, and a control valve 14. Thus, when the pump 11 is set in motion, and valve 14 open, fluid under pressure may be forced into cavity 6, check 5 valve 13 preventing back flow.

Fluid within cavity 6 may be exhausted therefrom, as through exhaust pipe 15 in which is disposed control valve 16.

It is also desirable to provide the supplemental means H, adapted to supply fluid under pressure to within the hull, and comprising a storage tank 17, receiving its supply from pump 11 through pipe 18 in which is disposed a control valve 19, and a delivery pipe 20 opens to within the cavity 6, and in which pipe is disposed control valve 21. Thus, even though pump 11 may be inactive, if there is a sufficient supply of fluid under pressure within tank 17, the 20 hull A may be raised by opening valve 21.

In order to prevent the escape of a sufficient amount of fluid from within the hull should the side become pierced accidentally or maliciously, and by a shell, and which 25 might interfere with the stability of the vessel, means J is provided and comprises a plurality of sets of plates 22 and 23, the plates of each set being disposed upright in close proximity to and movable toward 30 or from the walls of the hull. As a suitable means for movably supporting the plates, they may be hinged at their upper end portions to a rod 24 supported from the hull in any suitable manner. The lower 35 portions of the plates carry rollers 25 adapted to rest upon suitable supports 26, which, when the plates are hinged, should be formed arcuate in transverse section, as clearly shown in Fig. 2 of the drawing. I 40 also prefer to dispose the plates of one set, such as the plates 27 of set 22 in overlapping relation to the plates 28 of set 23, as clearly shown in Fig. 4 of the drawings. By this construction, should a shell pierce 45 the wall of the hull, the shell will engage one of the plates of set 22, which will yield slightly, and in the example shown, swing about its pivot point, having a tendency to compress the fluid within cavity 6, which is 50 already under pressure. Thus the plates not only serve as a shock-absorbing means, but due to the fluid pressure within the hull, move to effectively seal any opening which might occur in the hull walls.

55 While I show the ship or boat equipped with the usual propeller 30 and rudder 31 exteriorly of the hull A, it is to be understood that these devices may be placed in any practical position with respect to the hull, and if desired, in a more protracted position, such as extending below the open bottom B of the hull at both sides of, or to the rear of keel D.

From the foregoing it is made manifest 65 that I provide a boat or ship which is buoyed

wholly by fluid pressure coming directly upon the water, and that the relative position of the hull with respect to the water line may be changed by introducing more fluid under pressure to within the hull, or 70 exhausting a part of the fluid therefrom.

While I have herein shown and described my invention as applied to a relatively large ship, it is to be understood that the substance of my invention is applicable to 75 vessels of various types and over sea, as well as under sea boats.

Changes in details may be made without departing from the spirit or scope of my invention; but

I claim:

1. In a boat or ship, the combination of a hull with its open portion lowermost and its upper portion above the water line normally closed to the atmosphere, and a keel 80 below said open portion of the hull.

2. In a boat or ship, a hull providing a main cavity extending from wall to wall of the hull with its open portion lowermost and its upper portion above the water line 90 normally closed to the atmosphere.

3. In a boat or ship, the combination of a hull with its open portion lowermost and its upper portion above the water line normally closed to the atmosphere, a keel below 95 said open portion of the hull, and a waist about the upper portion of said hull.

4. In a boat or ship, the combination of a hull providing a main cavity extending from wall to wall of the hull with its open 100 portion lowermost and its upper portion above the water line normally closed to the atmosphere, and means for introducing fluid under pressure into said cavity.

5. In a boat or ship, the combination of a hull with its open portion lowermost and its upper portion above the water line normally closed to the atmosphere, a keel below 105 said open portion of said hull, and means for introducing fluid under pressure to within said hull.

6. In a boat or ship, the combination of a hull supported wholly by air trapped between the hull and the water, and means for varying the volume of the air trapped. 115

7. In a boat or ship, the combination of a hull with its open portion lowermost and its upper portion above the water line normally closed to the atmosphere, and a plurality of plates hinged within said hull adjacent the walls thereof. 120

8. In a boat or ship, the combination of a hull with its open portion lowermost and its upper portion above the water line normally closed to the atmosphere, and a plurality of plates within said hull adjacent the walls thereof, and arranged in staggered relation. 125

9. In a boat or ship, the combination of a hull with its open portion lowermost and 130

its upper portion above the water line normally closed to the atmosphere, a plurality of plates hinged at their upper portions within said hull adjacent the walls thereof, 5 and supports for the lower ends of said plates.

10. In a boat or ship, the combination of a hull with its open portion lowermost and its upper portion above the water line normally closed to the atmosphere, and a plurality of plates hinged at their upper ends within said hull adjacent the walls thereof, and provided with rollers at their lower portions, and supports carried by said hull upon 15 which said rollers engage.

11. In a boat or ship, the combination of a hull with its open portion lowermost and its upper portion above the water line normally closed to the atmosphere, and a plurality of plates hinged at their upper portions within said hull adjacent the walls thereof and provided with rollers at their lower portions, and arcuate supports carried by said hull upon which said rollers 20 engage.

12. In a boat or ship, the combination of a hull with its open portion lowermost and its upper portion above the water line normally closed to the atmosphere, and a plurality of sets of upright plates movably supported within said hull adjacent the walls thereof, the plates of one set being in overlapping relation with respect to the plates of the next adjacent set.

13. In a boat or ship, the combination of a hull, means for introducing and maintaining fluid under pressure within said hull, and a plurality of plates movably supported within said hull adjacent the walls thereof.

14. In a boat or ship, the combination of a hull, means for introducing and maintaining fluid under pressure within said hull, and a plurality of plates hinged within said hull adjacent the walls thereof.

15. In a boat or ship, the combination of a hull, means for introducing and maintaining fluid under pressure within said hull, and a plurality of plates hinged at their

upper portions within said hull adjacent the walls thereof. 50

16. In a boat or ship, the combination of a hull, means for introducing and maintaining fluid under pressure within said hull, a plurality of plates hinged at their upper portions within said hull adjacent the walls 55 thereof, and supports for the lower ends of said plates.

17. In a boat or ship, the combination of a hull, means for introducing and maintaining fluid under pressure within said hull, 60 a plurality of plates hinged at their upper portions within said hull adjacent the walls thereof, and provided with rollers at their lower portions, and supports carried by said hull upon which said rollers engage, 65

18. In a boat or ship, the combination of a hull, means for introducing and maintaining fluid under pressure within said hull, a plurality of plates hinged at their upper portions within said hull adjacent the walls 70 thereof and provided with rollers at their lower portions, and arcuate supports carried by said hull upon which said rollers engage.

19. In a boat or ship, the combination of a hull, means for introducing and maintaining fluid under pressure within said hull, and a plurality of sets of upright plates movably supported within said hull adjacent the walls thereof, the plates of one set 80 being in overlapping relation with respect to the plates of the next adjacent set.

20. In a boat or ship, the combination of a hull with its open portion lowermost and its upper portion above the water line normally closed to the atmosphere, and a plurality of plates movably supported within 85 said hull adjacent the walls thereof.

21. In a boat or ship, the combination of a hull with its open portion lowermost and its upper portion above the water line normally closed to the atmosphere, and a plurality of plates hinged at their upper portions within said hull adjacent the walls thereof. 90

CLARENCE WILBUR WHITE.
